UNITED STATES PATENT OFFICE

FRANS G. D. MULLER, OF HOUSTON, TEXAS, ASSIGNOR TO THE STAYTITE COMPANY, OF
HOUSTON, TEXAS, A CORPORATION OF TEXAS

DESIGN FOR A VALVE CASING

Application filed December 21, 1931. Serial No. 42,170. Term of patent 7 years.

To all whom it may concern:

Be it known that I, FRANS G. D. MULLER, a citizen of the United States, residing at Houston, in the county of Harris and State of Texas, have invented a new, original, and ornamental Design for a Valve Casing, reference being had to the accompanying drawings, forming a part hereof.

Fig. 1 is a top plan view of a valve casing

showing my new design, and Fig. 2 a side elevation thereof.

I claim:

The ornamental design for a valve casing, as shown.

In testimony whereof, I hereunto affix my signature.

FRANS G. D. MULLER.
